UNITED STATES PATENT OFFICE.

GEORGE W. BLAIR, OF MISHAWAKA, INDIANA, ASSIGNOR TO MISHAWAKA RUBBER & WOOLEN MANUFACTURING COMPANY, OF MISHAWAKA, INDIANA, A CORPORATION OF INDIANA.

SHOE.

Application filed April 1, 1925. Serial No. 19,770.

My invention has reference more particularly to the manner of building the soles onto the shoe and fastening the parts of the sole together and onto the shoe.

5 In the manufacture of shoes, it is a common practice to last the lower edge of the assembled upper to an inner sole and then attach the outer sole thereto. The soles are made up in various ways and numerous 10 methods have been employed for assembling and fastening the parts together. The Goodyear welt system is the one which is probably best known and consists in fastening welt strips around the edge of the assembled upper and inner sole and then stitching the outer sole to the edge of the 15 welt strip. Middle soles have also been used and stitched or otherwise fastened to the assembled upper and inner sole and the outer sole stitched to the edge of the middle sole. With these constructions, however, the outer sole and the upper are separately fastened to the welt strip or middle sole along spaced lines. Thus the upper portion 20 of the sole and the outer sole are not rigidly connected but may pull away from one another somewhat, depending upon the stiffness of the part of the middle sole or welt strip between the two lines of fastenings, and this is objectionable, as it permits 25 excessive strains on the welt strip or middle sole and on the stitches or other fastenings. Moreover, all the wear and tear is imposed on these separate lines of 30 fastenings and if they give way, there is nothing to hold the disconnected portions together. With my invention, an extra line of lock stitching is applied entirely through the inner, middle and outer soles and the 35 inturned edge of the upper, so that all the parts are drawn tight together and the excessive strain on the other lines of fastenings is thereby relieved. The upper is more 40 securely fastened to the sole and the parts of the sole are clamped together so as to 45 avoid lateral working of the parts of the sole, and the shearing action which is one of the most serious drawbacks in attaching the soles to a shoe by stitching. Furthermore, 50 in shoes having the soles made of rubber or rubber composition, such material does not afford a positive material for holding the stitches as does the leather, and the present invention is particularly well 55 adapted for attaching soles of composition.

The principal objects of my invention are to firmly fasten the shoe sole to the upper and likewise firmly fasten together the various layers of material composing the shoe sole; to reinforce and relieve the 60 strain on the fastenings which connect the middle sole respectively to the outer sole and the upper; to avoid any slipping action between the various layers of the sole at the points of connection; to provide an improved middle sole; to employ a lock stitch wherein the interengaged portions of the upper and lower threads are embedded in the shoe sole; and in general, to provide a shoe construction which is more substantial and 65 durable than in shoes which have heretofore been provided.

On the drawings:

Fig. 1 is a side view of a shoe embodying my improvements, with a portion of the toe 70 broken away to show the adjoining portions of the shoe sole in section;

Fig. 2 an enlarged bottom view of the forward part of the shoe sole, with a portion of the outer sole removed to disclose details of construction; and 75

Fig. 3 an enlarged sectional view, taken along the line of stitches which pass through the entire sole.

Referring to the drawings which show, 80 for the purpose of illustration, a common type of men's shoe, the reference numeral 1 indicates the upper, 2 the inner sole, 3 the middle sole and 4 the outer sole. The inner sole 2, which is preferably of leather, 85 is placed on the last in the usual manner, and has the edge of the upper and the edge of the lining 5, as well, in cases where a lining is employed, drawn over the edge of the inner sole 2, substantially as shown at 90 6 in Fig. 1, and fastened to it. A filling 7 of any suitable material such as cork fragments, is placed on the inner sole 2 in the space surrounded by the inturned edge 6 of the upper so as to fill in to the level of the 95 inturned edge of the upper, and after cementing the bottom of the shoe, the middle sole 3 is then laid over the bottom of the shoe and attached to the shoe by stitching with lock stitch to the inner sole as indicated at 100 8, said stitches being passed through the inturned edge 6 of the upper as shown in Fig. 1.

The outer sole 4 is then placed in position 105 after cementing both the surface of the mid-

110

dle sole and the surface of the outer sole and Goodyear stitched to the outer edge of the middle sole 3 as indicated at 9, thereby securing the outer sole in place against the middle sole 3.

- 5 With a construction such as I have just described, the middle sole serves as an intermediate member to which the upper portion of the shoe is attached and to which the outer sole is attached, and if either line of stitching loosens up or is not perfectly tight, relative movement of the several parts of the sole and upper takes place and the stitches are likely to be broken or sheared.
- 10 15 This is particularly true of the portion of the sole directly under the instep at the point where the sole is arched, as the bending of the shoe in walking imposes an excessive slipping strain on the layers of the sole at 20 this point.

To overcome the slipping tendency of the layers of the sole and to frictionally clamp the entire series of layers tight together, and also to furnish an additional fastening so 25 that the stitches 8 and 9 are not required to bear the entire strain, I employ a third line of stitches 10, which are at the inside of the lines of stitches 8 and passed entirely through the outer, middle and inner soles 30 and also through the inturned edge 6 of the upper as well. These stitches are drawn up tight, so as to clamp the various layers of the sole and the inturned edge of the upper in close frictional contact and any separating 35 tendency which would ordinarily occur between the inner sole 2, and the outer sole 4 is thereby obviated and the effectiveness of the stitching 8 and 9 thereby materially increased.

- 40 The stitching 10 consists of a lock stitch comprising separate inner and outer threads 11 and 12 respectively, which have interengaging looped portions, and the point of interengagement is located well within or embedded in the shoe sole as indicated, for example, at 13, so that the interlocked portions are thoroughly concealed and protected against damage.

In practice, when an outer sole of rubber 50 composition is employed, a layer of fabric 14 is vulcanized to the top surface of the outer sole 4 so as to reinforce the composition and prevent stretching or bulging of the sole 4, and in the finished shoe an insole 15 55 is cemented to the inner surface of the inner sole 2 and extends over and covers the stitches 8 and 10.

In the shoe which is illustrated herein, the middle sole 3 is of a special construction, 60 shown in detail in Fig. 3 and comprises a thin sheet of leather reinforcing material 16, which is vulcanized between two thin layers 17 and 18 of rubber composition. This form of middle sole need not necessarily be 65 employed, but is desirable, as it serves to

waterproof the sole and being extremely flexible, does not stiffen the sole materially and this is important in heavy shoes, as the soles thereof are usually uncomfortably stiff.

The middle sole with leather center, in addition to affording flexibility and waterproofing, also affords a substantial and tenacious body which will securely hold the stitches and prevent them from pulling through the middle sole, as they might do, if the middle sole were made entirely of rubber composition. Furthermore, as the shoe is used, a middle sole made entirely of rubber composition has a tendency to stretch out and buckle between the middle and outer soles, but when the leather center is used, this prevents stretching out of the rubber composition, and the middle sole is caused to maintain its original form.

The outer sole 4 may be of any suitable material, as for example, either leather or rubber composition, the latter being particularly desirable in heavy shoes because of its wearing properties and also because it is more flexible than leather and makes a more comfortable shoe.

This method of construction gives the outer sole two distinct and independent lock stitch seams for attaching it to the shoe. The outer seam holds it securely to the middle sole and prevents it opening on the edge and admitting moisture, while the inner seam attaches the outer sole not only to the middle sole, but also to the lasted upper and the inner sole. This bonds all layers of the shoe together so tightly that there is no lateral motion between them when flexed, consequently the stitches do not cut off. The middle sole being attached to the shoe through the lasted upper and inner sole by an integral set of stitches, is protected at all times from outside wear and will not come loose from the shoe. In case the outer sole in wear is worn thin at the toe or on the edges thereby destroying the holding effect of the outer seam, the sole cannot become detached from the shoe because the inner seam is set back far enough from the edge so that it still holds the outer sole tightly to the shoe.

While I have shown and described my invention in a preferred form, I am aware that various changes and modifications may be made without departing from the principles of my invention, the scope of which is to be determined by the appended claims.

I claim as my invention:

1. In a shoe the combination of inner and outer soles and an intermediate sole, separate fastenings connecting the inner and outer soles to said intermediate sole, and a continuous line of stitches around the toe, ball and shank portions and extending through and connecting the inner and outer soles and said intermediate sole.

2. In a shoe the combination of inner and outer soles and an intermediate sole, an upper having the lower edge turned in under the marginal portion of the inner sole, 5 separate fastenings connecting the inner sole and inturned edge of the upper to the intermediate sole and the outer sole to said intermediate sole, and a continuous line of stitches around the toe, ball and shank portions and extending through and connecting the inner and outer soles and the intermediate sole.
3. In a shoe the combination of inner, outer and middle soles and an upper having the lower edge thereof turned in between the marginal portions of the inner and middle soles, laterally spaced rows of fastening means extending respectively through the middle and inner soles and the inturned edge 10 of the upper, and through the middle and outer soles, and a continuous line of stitches around the toe, ball and shank portions and extending through and uniting the inner, middle and outer soles and the inturned edge 15 of the upper.
4. In a shoe, the combination of inner, middle and outer soles and an upper having the lower edge thereof turned in between the marginal portions of the inner and middle soles, and three laterally spaced lines of 20 stitches wherein the outer line of stitches connects the middle and outer soles, and the middle line of stitches connects the inner and middle soles and the inturned edge of the upper and the inner line of stitches connects the inner and middle and outer soles and the inturned edge 25 of the upper.
5. In a shoe the combination of inner and middle soles, an upper having the lower edge thereof turned in between the marginal portions of the inner and middle soles, fastening means uniting the inner and middle soles and the inturned edge of the upper, an outer sole covering said fastening means 30 and having a row of stitches adjacent the edge whereby it is secured to the edge of the middle sole, and a line of stitches remote from said row of stitches and engaging through the inner, middle and outer soles 35 and the inturned edge of the upper and comprising upper and lower threads having corresponding loops interengaged within the assembled sole structure.
6. In a shoe, the combination of inner and outer soles, and a middle sole interposed between and independently fastened respectively to the inner and outer soles, said middle sole being formed with a layer of reinforcing material interposed between and 40 united to outer layers of rubber composition so that the layer of reinforcing material serves as an anchorage for the stitches.
7. In a shoe, the combination of inner and outer soles, a sheet of leather interposed between the inner and outer soles and having 45 a facing or rubber thereon at each side consolidated therewith and interposed respectively between the inner sole and the sheet of leather and the outer sole and the sheet of leather, and two spaced lines of stitches 50 engaging respectively with the inner sole and the outer sole and having their inner extremities looped through the sheet of leather.
8. The art of manufacturing a shoe 55 which comprises fastening the edge of the upper between an inner sole and a middle sole, then stitching an outer sole to the edge of said middle sole, and then applying a continuous line of stitches around the toe, ball and shank portions of the shoe and through the inner and outer soles and the said middle sole.
9. The art of manufacturing a shoe, 60 which comprises fastening the edge of the upper between marginal portions of inner and middle soles, then stitching an outer sole to the edge of the middle sole and then applying a continuous line of stitches around the shoe continuing along the toe, ball and shank portions thereof and through the inner, middle and outer soles and the edge of the upper.
10. The art of manufacturing a shoe, 65 which comprises interposing the edge portion of the upper between an inner and a middle sole, simultaneously stitching said edge portion to the inner and middle soles, then stitching an outer sole to the edge of the middle sole, and then applying an inner 70 line of stitches through the inner, middle and outer soles and the edge of the upper and interlocking the upper and lower threads thereof substantially midway between the upper and lower surfaces of the 75 entire sole.
11. In a shoe the combination of inner and outer soles and an intermediate layer, separate fastenings connecting the inner and outer soles to said layer and a continuous 80 line of lock stitches around the toe, ball and shank portions and extending through and connecting the inner and outer soles and said intermediate layer, the interengaged 85 loop portions of said lock stitches engaging 90 against the lower face of said intermediate layer.
12. In a shoe the combination of inner and outer soles, a middle sole interposed between and independently fastened respectively to the inner and outer soles, said middle sole being formed with a layer of reinforcing material interposed between and united to outer layers of rubber composition, and a continuous line of lock stitches around the 95 toe, ball and shank portions and extending through and connecting the inner and outer soles and said middle sole, interengaged loop portions of said lock stitches engaging 100 against the lower face of said middle sole.

13. In a shoe, the combination of inner and outer soles, and a middle sole interposed between the inner and outer soles, said middle sole being formed with a layer of reinforcing material interposed between and united to outer layers of rubber composition, and laterally spaced lines of stitches
- 5

engaging respectively with the inner sole and the outer sole and having their inner extremities looped through the sheet of reinforcing material so that the layer of reinforcing material serves as an anchorage for the stitches. ¹⁰

GEORGE W. BLAIR.
